FIG. 1.

UNITED STATES PATENT OFFICE.

ARTHUR HANCOCK AND HUBERT S. HEATH, OF 406 EUSTON ROAD, MIDDLESEX COUNTY, ENGLAND.

LIQUID-METER.

SPECIFICATION forming part of Letters Patent No. 234,275, dated November 9, 1880.

Application filed May 15, 1880. (No model.) Patented in England May 23, 1879.

To all whom it may concern:

Be it known that we, ARTHUR HANCOCK and HUBERT SAMUEL HEATH, both of No. 406 Euston Road, in the county of Middlesex, 5 England, have invented a new and useful Improved Liquid-Meter, (for which we have obtained a patent in Great Britain, No. 2,056, bearing date May 23, 1879,) and of which the following is a specification.

10 This invention relates to meters for measuring and registering the volume of water or other liquid passed through them, the chief objects of the invention being to obtain simplicity in the construction of the apparatus 15 and accuracy and durability in its operation.

The accompanying drawings show the construction which we adopt.

Figure 1 is a longitudinal section, and Fig. 20 2 is a transverse section, of the meter; and Fig. 3 is a front view of the connections for working the slide.

The liquid enters by a supply-pipe, A, into the regulating-chamber B, in which is a float, C, connected to the arm of a stop-cock, a, 25 which, being closed more or less as the float C rises, stops or throttles the supply, so as to govern the pressure within the meter. From the regulating-chamber B the liquid flows by a passage, b, to the middle of three ports arranged on a horizontal facing and governed by a slide, D. This slide works within a chamber, from which opens the outlet E of the meter. The two side ports, d' d'', communicate, respectively, with two compartments, G' G'', into 30 which the body of the meter is divided by a partition, F, which, not reaching the top of the meter, leaves free communication between the upper parts of the two compartments. In each compartment is a float, g' g'', fixed at the

40 opposite ends of an equal-armed lever or sway-beam, H. The rocking axis h of this lever extends into a front compartment, K, and to its extended part is fixed an arm, L, having at its lower end a slot in which works an anti-friction-roller on a crank-arm of a rocking shaft, M. This arm, extended upward, carries a tumbling weight, N, which can fall against either of two spring-stops, n' n''. The extended axis h also carries a spring-pawl engaging with 45 the ratchet-wheel of an ordinary counter, O,

provided with dials and indices to register gallons or other units of liquid-measure, and multiples thereof, in the usual way, the dials being visible through a glass, k, fixed in the front of the meter. The rocking shaft M extends into the compartment containing the slide D, and has a wing-arm, m, projecting down from it into a gab on the upper side of the slide D, the gab being wider than the wing. 55

In a meter constructed as above described 60 we find certain details of advantage, which details are as follows: In the supply-pipe A we introduce a filter or sieve, consisting of a piece of pipe, f, closed at the top, projecting upward, and drilled with a number of small holes 65 over its surface. This prevents access of dirt or grit to the meter, and as the impurities arrested by it are deposited on its outer surface it can be readily cleansed. The regulating-cock a, being for the purpose of throttling the 70 supply, is made a somewhat loose fit, so that the float C can freely work it, and this float has a guide-rod, e, working freely in a guide-tube at the bottom of the regulating-chamber B. The slide D is made, as shown, with its 75 end curving outward, so that the liquid issuing from either side port into the slide-chamber is deflected laterally, and issues by the outlet E without rising in the slide-chamber to the height of the rocking shaft M. This rocking shaft M, as well as the rocking axis h of the sway-beam H, where it passes through the partition, is coned to fit as a valve against a conical seating in the partition, and is pressed into its seat by a light spring, S, at the back 80 end of the axis. Behind the outlet-mouth E there is a passage terminating in an open slit, e, by which liquid can escape if there be a greater discharge than can issue by the mouth E. 85

The operation of the meter may be described 90 as follows: The liquid is supplied by the pipe A, and, being filtered in its passage by the filter f, and throttled more or less by the stop-cock a, enters the regulating-chamber B. If it enters this chamber faster than it can issue therefrom by the passage b the float C rises, still further throttling the supply. Thus, as there are at the top of the chamber B apertures i for free passage of air, there can never be greater pressure of liquid in the 95 100

meter than what is due to the height of column in B, floating C at or about its normal level. Within the meter we will suppose the liquid to be low in the compartment G^2 and high in G' , the float g^2 therefore being down and g' being up, the beam H canted so that its arm L is in the position shown in Fig. 3, and consequently the tumbling-weight N resting on its stop n' . The slide D has, therefore, by the wing m , been moved to the right, uncovering the port d' and making a communication from b to d' . Liquid from B now flows by the passage b and port d' into the compartment G^2 , while liquid flows from G' by the port d' into the slide-chamber, and issues thence by the outlet E. After a certain time the level of the liquid in G^2 has risen, and that in G' has sunk so far that the floats g', g^2 are sufficiently out of balance to overcome the gravity of the weight N, which, as it begins to move upward from the stop n , becomes less effective till it passes the vertical line over the axis M, after which it becomes effective in the opposite direction, with force increasing as it moves. The floats are thus caused to make a rapid stroke, g^2 rising and g' descending. At the same time the axis M, turning rapidly from its one extreme to the other, the wing-arm m on it acting during the latter part of its stroke against the left side of the gab in the slide D, moves the slide suddenly to the left, so as to uncover the port d^2 and bring d^2 into communication with b . The compartment G' now receives a supply of liquid, while liquid is discharged from G^2 , and after a time the reversal of action ensues, as above described. Each stroke in one direction of the beam H causes a movement to be imparted to the counter O

by means of the pawl on the arm of h acting on the ratchet-wheel of the counter. The charge of the compartments G' and G^2 for each such stroke being a known quantity, the counter O, which registers the number of these strokes, records the quantity of liquid that passes through the meter.

Having thus described the nature of the said invention, and in what manner the same is to be carried into practical effect, we claim—

1. In liquid-meters, the combination of the meter divided into two chambers by a vertical partition, F, the sway-beam provided with the floats at opposite ends thereof, the slide D, intermediately connected with the sway-beam by the slotted arm and rocking shaft with tumbling-weight, and the ports d', d^2 , substantially as and for the purpose specified.

2. In combination with the sway-beam H, floats g', g^2 , slide D, and ports d', d^2 , the arm h operating on a counter by means of a pawl for registering the movements of the sway-beam and floats, substantially as described.

3. In combination with the compartments G', G^2 , sway-beam H, floats g', g^2 , slide D, and ports d', d^2 , the regulating-vessel B, float C, and regulating cock or valve a, the whole constructed and operating substantially as and for the purpose described.

In testimony whereof we have signed our names to this specification, in the presence of two subscribing witnesses, this 30th day of April, A. D. 1880.

ARTHUR HANCOCK.

HUBERT SAMUEL HEATH.
